UNITED STATES PATENT OFFICE.

GEORGE F. KENNEY, OF STERLING, MASSACHUSETTS, ASSIGNOR OF ONE-HALF TO
CARL B. DREVITSON, OF SOMERVILLE, MASSACHUSETTS.

PISTON RING.

Application filed November 1, 1927. Serial No. 230,332.

This invention relates to a resilient piston-ring transversely divided at one side and having end portions normally sprung apart by the resilience of the ring, and a resilient 5 ring-shaped expander, also divided at one side and adapted to bear simultaneously on portions of the internal surface of the ring, and on portions of the bottom of a piston groove receiving the ring, to radially expand 10 the ring and press the periphery thereof against the internal wall of a cylinder.

The object of the invention is to provide a piston-ring and an expander therefor, so formed that when combined and in use, the 15 expander will not only expand the ring radially, but also edgewise or laterally, and press the edge faces of the ring against the sides of the piston groove.

Of the accompanying drawings forming 20 a part of this specification,—

Figure 1 is a perspective view of a piston-ring and an expander therefor, constituting the preferred embodiment of the invention.

Figure 2 is an edge view of the ring looking 25 toward the side opposite the split shown in Figure 1.

Figure 3 is a section on line 3—3 of Figure 1.

Figure 4 shows the ring and expander in 30 section on line 3—3 of Figure 1, and a portion of a piston, in a groove of which the ring is expanded edgewise.

Figure 5 is a section on line 5—5 of Figure 1.

Figure 6 is a fragmentary view, showing 35 a portion of the ring without the expander, looking toward the inner side of the ring.

Figure 7 is a view similar to Figure 1, showing a different embodiment of the in- 40 vention.

Figure 8 is a fragmentary view, showing portions of the ring and expander shown by Figure 7, looking toward the inner side of the ring.

Figure 9 is a view similar to Figure 8, 45 omitting the expander.

Figure 10 is a section on line 10—10 of Figure 9.

Figure 11 is a section on line 11—11 of Figure 9.

Figure 12 is an edge view of the portions of the ring and expander shown by Figure 8.

The same reference characters indicate the same parts in all of the figures.

55 The ring shown by Figures 1 to 6, in-

clusive, is of resilient metal, and is transversely split at one side, its end portions 12, 12, being normally sprung apart by the resilience of the ring. In the ring are formed a plurality of peripheral slots, extending parallel with the edge or side faces of the ring, and partially subdividing the ring into two zones 13, 13, adapted to be sprung apart, to widen the ring at intervals, as indicated by dotted lines in Figure 6. In this instance, 60 there are two end slots 14, closed by the end portions 12, and an intermediate slot 15 (Figure 2) closed by neck portions 16, 16, connecting the zones 13. The internal face of the ring has a groove coextensive with 65 the ring and provided with oppositely beveled side faces 17.

With the ring thus formed, I combine a resilient, transversely divided, normally expanded ring-shaped expander, having a zig-zag form and adapted to bear simultaneously on the beveled faces 17, and on the bottom 18 of a ring-receiving groove, in a piston 19 (Figure 4) in which the ring and expander are inserted. The expander, in the preferred 70 embodiment of the invention, is a flat-sided, 75 resilient metal strip of polygonal form, and includes salient bends 20, formed to bear on the beveled faces 17, as shown by Figures 3 and 4, and intermediate flat portions 21, 80 formed to bear on the groove bottom 18.

The split or division of the expander is indicated at 22 in Figure 1.

When the ring and expander are assembled preparatory to insertion in a piston groove, the ring being expanded to its normal diameter, the bends 20 of the expander bear lightly on the beveled faces 17 of the ring, as indicated in Figure 3, and do not expand the ring sidewise. When the assembled ring and expander are inserted in a piston groove, and the piston and ring are inserted in a cylinder, the ring is contracted by the cylinder wall, and the expander is at the same time backed by the bottom of the 90 piston groove. The expander is, therefore, tensioned, and not only acts to increase the radial pressure of the ring on the cylinder wall, but also acts by its pressure on the beveled faces 17 of the ring to laterally expand 95 the ring, as indicated by Figure 4, and force the side or edge faces of the ring against the sides of the piston groove. The portions of the expander which bear on the beveled faces 17, are preferably beveled, as shown by 100 105 110

Figures 3, 4, and 5, to conform to the bevel of said faces.

In the embodiment shown by Figures 7 to 12, the ring is transversely split at one side, and provided with the end portions 12, the zones 13, 13, the slots 14, 14 and 15, and the necks 16, connecting the zones, as in the embodiment first described.

The internal groove of the ring has beveled side faces 17^a which are wider than the faces 17, and extend to the slots 14 and 15.

The expander is preferably made of resilient wire and includes central portions 24, lying in the center or bottom of the internal groove of the ring, and oppositely inclined bends bearing on the beveled faces 17^a, each bend including the inclined portions 25 and the outer portions 26. The split of the expander is indicated at 27 (Figure 7).

When the ring and expander are assembled prior to their insertion in a piston groove and piston, the expander portions 26 project from the internal surface of the ring, as shown by Figure 12, the ring having its normal width. When the ring and expander are inserted in a piston groove, and the piston is inserted in a cylinder, the expander is tensioned by contact of its portions 26 with the groove bottom, and contact of the ring with the cylinder wall, the result being a sidewise expansion of the ring, as before.

The dotted line X in Figure 4, indicates

a portion of the internal surface of the cylinder.

I claim:

A transversely split resilient piston ring having end portions normally sprung apart by the resilience of the ring, a plurality of peripheral slots extending parallel with the edges or side faces of the ring and partially subdividing the ring into zones adapted to be sprung apart, to widen the ring at intervals, there being two end slots closed by the end portions of the ring, and an intermediate slot closed by neck portions of the ring connecting said zones, the internal face of the ring having a groove coextensive with the ring and provided with oppositely beveled side faces, combined with a transversely divided, normally expanded, resilient ring-shaped expander, having a zigzag form and adapted to bear simultaneously on said beveled faces, and on the bottom of a piston groove, the arrangement being such that when the ring and expander are inserted in a piston groove, and the piston is inserted in a cylinder, the expander exerts a radial expanding force on the ring, to press the periphery thereof against the cylinder wall, and a lateral expanding force on the ring zones, to press the edge faces of the ring against the sides of the piston groove.

In testimony whereof I have affixed my signature.

GEORGE F. KENNEY.
